UNITED STATES PATENT OFFICE.

CHARLES T. ERICSSON, OF BIRMINGHAM, ALABAMA, ASSIGNOR TO BIRMINGHAM MACHINE & FOUNDRY COMPANY, A CORPORATION OF ALABAMA.

QUICK-REMOVABLE BREECH-BLOCK FOR HYDRAULIC CYLINDERS.

1,369,014.

Specification of Letters Patent. Patented Feb. 22, 1921.

Application filed July 17, 1919. Serial No. 311,631.

To all whom it may concern:

Be it known that I, CHARLES T. ERICSSON, a citizen of the United States of America, residing at Birmingham, in the county of 5 Jefferson and State of Alabama, have invented certain new and useful Improvements in Quick-Removable Breech-Blocks for Hydraulic Cylinders, of which the following is a specification.

10 My invention relates to a quick removable breech block or plug for hydraulic cylinders and particularly for the hydraulic cylinders of sugar mills.

It is very essential that the repacking and 15 replacing of the hydraulics on sugar mills at the plantation during the grinding season should be done as quickly as possible, and with this end in view I have designed a new hydraulic breech block which requires no 20 disconnection of hydraulic piping or any other parts and no unscrewing of bolts except one small lock bolt, in order to lift out the hydraulic breech block and piston of the cap.

25 The particular object of my construction is to obtain the greatest strength of attachment for the block with the least time required to remove and replace it and I attain this by the provision of a breech block having teeth on its opposite sides which can with a quarter turn be brought into engagement with similar teeth in the top cap of the cylinder.

30 A further object of my invention is to 35 provide the breech block with a pair of lugs which co-act with a fixed pin to arrest the block in engaged or disengaged position, a removable stop pin being also provided to coact with the other in engaging said lugs 40 so as to positively hold the breech block against rotation in the top cap.

45 My invention also comprises the novel details of construction and arrangement of parts, which in their preferred embodiment only are shown in the accompanying drawings which form a part of this specification, and in which:—

50 Figure 1 is a partial end elevation of a sugar mill with the hydraulic cylinder in its top cap shown in vertical section and its breech block shown in partial section in operating position.

Fig. 2 is a plan view of the top cap with

the breech block removed and the bolts shown in section.

55 Fig. 3 is a detail plan view of the breech block showing both stop pins in operating position.

Fig. 4 is a vertical section through the top cap with the breech block shifted into released position ready to be lifted out.

60 Similar reference numerals refer to similar parts throughout the drawings.

As illustrated, 1 is typical of any sugar mill which is provided with a ram 2 working 65 in a hydraulic cylinder 3 in its top cap 4. The water inlet 5 is taken through the side of the cap and tapped into the heavy brass bushing 6 near its middle.

70 In the top cap there are a number of circular saw-tooth-shaped teeth 7 cut which extend only through an arc of 90°, less clearance, on two opposite sides of the cylinder, as indicated in Fig. 2, and the breech block 8 has corresponding teeth 9 cut to gage so 75 as to accurately match teeth in the cap. When working the breech block is in position with all of its teeth 9 engaged with teeth 7 in the cap and is so held by a pin 10 and a tap bolt 11 which match in the oppositely facing hook lugs 12 spaced 90° apart on the top of the breech block and disposed to overlap the top cap. The pin is made fast in the top 90° removed from the threaded hole tapped in the cap for the bolt 11.

80 Now in order to lift out the breech block all it requires is to unscrew the bolt 11 and turn the breech block around 90° by means of a wrench fitted over the square 13 on top of the breech block, until the slot in the 90 breech block comes to positive stop against pin 10, when the breech block can be lifted out.

85 To replace the block, it is lowered back into the cylinder with its teeth 9 just clearing the cap teeth 7 and is given a 90° turn which again engages the teeth, after which the bolt 11 is screwed back in place and the lugs 12 are held by the bolt 11 on one side and the pin 10 on the other. The idea of 100 having a plurality of circular teeth 7 and 9 is to distribute the pressure on as large a surface as possible.

105 This invention is not intended to be restricted in scope to the specific embodiments shown, but contemplates such modifications

as come within the spirit and scope of the claim.

What I claim as new and desire to secure by Letters Patent, is:—

- 5 A sugar mill cap comprising a hydraulic cylinder with opposite sets of teeth subtending an arc of approximately 90° , a breech block with complementary teeth adapted to be engaged with the cap teeth by a quarter
- 10 turn of the block, a water inlet entering the cylinder below the block, a top flange on the block adapted to rest on the top of the cap,

a pair of stop shoulders spaced 90° apart on said flange, a fixed pin adapted to be engaged by both shoulders as the breech block 15 is shifted from released to engaged position and vice versa, and a removable pin adapted to coöperate with the fixed pin in engaging the two shoulders simultaneously to lock the breech block in its engaged position.

In testimony whereof I affix my signature.

CHARLES T. ERICSSON.
